DESIGN FOR A DRESS

Elizabeth T. Romaine, New York, N. Y.

Application January 14, 1937, Serial No. 67,044

Term of patent 3½ years

To all whom it may concern:

Be it known that I, Elizabeth T. Romaine, a citizen of the United States, residing at New York city, in the county of New York and the State of New York, have invented a new, original, and ornamental Design for a Dress, for which the following is a specification, reference being had to the accompanying drawing, forming part thereof.

In the accompanying drawing, Fig. 1 is a front perspective view; and Fig. 2 is a rear perspective view of a dress showing the new design.

I claim:

The ornamental design for a dress, as shown.

ELIZABETH T. ROMAINE.
